ELECTRIC HEATER UNIT

Roger L. Crispell, Birmingham, Mich., assignor to General Motors Corporation, Dayton, Ohio, a corporation of Delaware

Application February 10, 1955, Serial No. 34,457

Term of patent 7 years

(Cl. D81—10)

Fig. 1

Fig. 2

Fig. 3

Fig. 4

Fig. 5

Figure 1 is a perspective view of an electric heater unit embodying my new design placed in vertical position when not in use showing the bottom, front and side;

Figure 2 is a perspective view of the unit in a horizontal position ready for use showing the top, front and the same side;

Figure 3 is a top view of the unit in vertical position as shown in Figure 1;

Figure 4 is a side view of the unit shown in vertical position in Figure 1; and

Figure 5 is a side view of the unit shown in folded down position in Figure 2.

The dominant features of my design reside in the portions shown in full lines.

I claim:

The ornamental design for an electric heater unit, as shown.
